NAIL CLINCHING APPARATUS

Gail H. Templin, Bldg. 6, Airbase, Vero Beach, Fla.

Filed Apr. 16, 1959, Ser. No. 806,832

6 Claims. (Cl. 1—1)

This invention relates broadly to automatic apparatus for clinching nails and the like connecting elements which have been driven through members so that their ends project therefrom, and in its more specific aspects this apparatus has been developed and perfected especially for automatically clinching nails which have been driven through adjacent assembled members of structural trusses used in the building arts and for handling a succession of trusses as the clinching operation is being performed; and the nature and objects of the invention will be readily recognized and understood by those skilled in the arts to which it relates in the light of the following explanation and detailed description of the accompanying illustrations illustrating what I at present believe to be preferred embodiments or mechanical expressions of my invention from among various other forms, arrangements, combinations and constructions, of which the invention is capable within the spirit and scope thereof.

The use of trusses of various types which are constructed of wood has been greatly stimulated during recent years because of the tremendous increase of large housing developments wherein the types of buildings being erected lend themselves to the use of wood trusses.

This demand for large numbers of such structural trusses has posed a problem in their fabrication and has resulted in my invention which reduces the time required in fabrication while insuring a structurally sound truss. I have developed an apparatus by which trusses in large numbers may be economically completed following partial assembly of the various components of the truss. While the apparatus which I have devised substantially reduces the time required for truss fabrication it also reduces the labor required in constructing and finishing structural trusses to thereby help make the fabrication of structural trusses an economically feasible operation.

The components or members forming a structural truss of the character in which I am particularly interested may be joined together by means of metal truss lock plates which extend across adjacent members, one plate being on each side, and are secured to the components to connect them together by means of nails driven through the plates and the components. The nails which I use are of greater length than the combined thickness of the two plates and the truss components at the joint so that the pointed ends of the nails project beyond the lower or second plate when the nail heads are in engagement with the upper or first plate. In order to strengthen the truss at the joints it is desirable to clinch or bend over the projecting nail ends against the second truss lock plate and it has been my purpose to provide an automatic machine for clinching the aforesaid projecting nail ends.

I have devised an apparatus into which an assembled truss is fed with the nail ends projecting as described above, and which automatically draws the assembled truss therethrough while clinching the nails at every joint in the truss and ejecting the fully completed and assembled truss. In using the apparatus one truss after another may be fed thereinto in a rapid and sure operation.

2

I have recognized the fact that there are many types of trusses and that the joints which are to be operated on will not always be in the same relative positions, for I have designed my apparatus so that it will effect its clinching function on many types and sizes of trusses, and in many instances no adjustment of the machine will be necessary.

While I have provided an apparatus which reduces necessary adjustments to a minimum, I have, in one form of apparatus, provided for adjustment when necessary, however, I have evolved a further form of machine in which adjustments are automatically performed by the machine itself.

It has been one of my objects to produce an apparatus which is sturdy and of simple construction and operation so that it will operate for long periods of time with a minimum of maintenance care. I have also devised an apparatus which is economical to produce and operate.

The apparatus of this invention eliminates manual nail clinching and insures that every nail used at a truss joint will be fully and adequately clinched to provide a strong and safe joint. Thus, the chance of poor or incomplete clinching of former clinching methods is completely eliminated by my apparatus.

While I have particularly described my invention as adapted to clinch nails which have been driven through truss lock plates connecting adjacent components of trusses together it is to be distinctly understood that my apparatus will function equally well in securing truss lock plates to and across components of trusses, which truss lock plates are formed with struckout portions which form tangs which are adapted to be embedded in the wood components of the truss. My apparatus will operate on such joints and will function to embed the tangs of the truss lock plates into the wood truss components.

With the foregoing general objects, features and results in view, as well as certain others which will be apparent from the following explanation, the invention consists in certain novel features in design, construction, mounting and combination of elements, as will be more fully and particularly referred to and specified hereinafter.

In the accompanying drawings:

Fig. 1 is a view in end elevation of the nail clinching apparatus, with parts thereof in section and with parts thereof broken away.

Fig. 2 is a view taken on line 2—2 of Fig. 1.

Fig. 3 is a vertical sectional view through the rollers of the apparatus and illustrating a truss feeding through the apparatus and the nails at a joint thereof being clinched.

Fig. 4 is a sectional view in end elevation, with parts thereof being broken away, of a modified form of mounting for the rollers.

Fig. 5 is a sectional view in end elevation, with parts thereof being broken away, of a modified form of nail clinching apparatus.

Fig. 6 is a detailed view of a joint of a truss having truss lock plates formed with tangs adapted to be embedded in the wood truss components, the truss being fed into the apparatus.

In the accompanying drawings I have shown a supporting table or platform upon which the apparatus may be mounted, such table or platform may be of generally rectangular shape and may comprise a bed 1 mounted on legs 3 having a shelf 5 extending between each pair of front and rear legs. Mounted on the bed 1 of the table are pairs of upstanding spaced front and rear roller supporting members 7 which may be connected at their top ends by reinforcing bridge members 9. The upstanding pairs of supporting members may be of any type or shape suitable for the purpose; however, each should have an inner wall 11, so that pairs of opposed

walls 11 on the upstanding supporting members are provided.

Operatively mounted on and extending between the two forward supporting members 7 are a pair of forward clinch rollers designated generally by the numeral 13 and a pair of rear feed rollers designated generally by the numeral 15 are operatively mounted on and extend between the two rear supporting members 7.

The pair of clinch rollers comprises an upper roller 17 and a lower roller 19. The clinch rollers are formed of metal, such as low carbon steel and, as one example, may be of a diameter of the order of 7". The upper clinch roller is rotatively mounted in journal brackets 21 at each end, and each bracket is mounted on a wall 11 of a front supporting member 7. The journal or bearing brackets 21 for the upper clinch roller 17 are mounted on walls 11 of the supporting members for vertical adjustment with respect thereto by means of nuts and bolts 23 which extend through the bearing brackets and through vertically elongated slots 25 which are formed in each wall 11. It will now be appreciated that by loosening the nuts the bearing brackets may be vertically adjusted and locked in the desired adjusted position to thereby position clinch roller 17 in any predetermined vertical position.

The lower clinch roller 19 is mounted or rotatively journaled at each end in journals 27 which are mounted on bed 1 of the supporting table and are horizontally adjustable by means of nuts and bolts 29 which extend through slots 31 in the bed. Thus, through the vertical adjustment of roller 17 the vertical spacing between that roller and roller 19 may be varied and through the horizontal adjustment of roller 19 the axial plane of that roller may be moved relative to that of roller 17.

The pair of feed rollers 17 comprises an upper feed roller 33 and a lower feed roller 35. The feed rollers are formed of rubber, for example, they may comprise an operative surface of approximately 1/2" thickness of neoprene rubber—42 x 50 durometer hardness. This rubber surface may, of course, cover any suitable type of metal roller 34. My nail clinching apparatus has operated successfully where the feed rollers 15 were of approximately 8" in diameter.

The upper rubber feed roller 33 is rotatively mounted on and extends between the walls 11 of the rear supporting members 7, the roller being mounted for vertical adjustment in generally the same manner as clinch roller 17. A pair of journal brackets 37, rotatively support roller 33, the brackets 37 being fixed to walls 11 by means of nuts and bolts 39 which extend through vertical slots 41 in walls 11.

The lower rubber feed roller 35 is rotatively mounted beneath and spaced from roller 33, the lower roller being journaled in brackets 43 fixed to bed 1 of the supporting table. The lower feed roller 33 is a fixed roller and is preferably neither vertically or horizontally adjustable and the axes of the two feed rollers are preferably in vertical alignment.

I provide two motors 45 and 47, one being mounted on one shelf 5 and the other being mounted on the other shelf of the supporting table. The motors drive the pairs of rollers at the same speed and may be electrically powered.

The motor 45 is provided with a drive shaft 49 which may extend therefrom (through suitable gearing) beyond the table and has a sprocket wheel 51 on the end thereof. The upper rubber feed roller 33 has a shaft 53 extending from the end thereof and beyond the supporting members 7 and above drive shaft 49 and a sprocket wheel 55 is fixed on the end of the shaft 53. The upper feed roller 33 is operatively connected to motor 45 and is driven thereby by means of chain 57 extending between and operatively connected to sprockets 51 and 55. If desired an idler sprocket 59 rotatively mounted on a pivot arm 61 biased by spring 63 and in

engagement with chain 57 may be provided to accommodate slack in the chain.

The upper metal clinching roller 17 is operatively connected to feed roller 33 and is driven thereby when the feed roller is rotated upon operation of motor 45. The upper metal clinch roller 17 is provided with a stub shaft 65 extending from the same end thereof that shaft 53 extends from roller 33, however, the length of shaft 65 is reduced relative to the length of shaft 53. A sprocket wheel 67 is fixed on the end of shaft 65 and a sprocket chain 69 extends over and is operatively connected to sprocket wheel 67 and extends therefrom to and around a further sprocket wheel which is fixed on shaft 53 of feed roller 33, the last mentioned sprocket wheel being fixed on shaft 53 inwardly thereof with respect to sprocket wheel 55. Thus when the motor 45 is operating roller 33 will be caused to rotate and will, in turn, cause the rotation of upper clinch roller 17. Thus, the two upper rollers of the pair of rollers are driven by the motor 45 and rotate in a clockwise direction.

Now, as will be explained, the two lower rollers 19 and 35 are driven by the motor 47 which has a drive shaft 71 extending outwardly (through any suitable gearing) of the legs 3 of the supporting table at the opposite side thereof from which drive shaft 49 extends. A sprocket wheel 73 is fixed on the end of drive shaft 71. The lower metal clinch roller 19 has a shaft 75 extending from an end thereof to which an inner sprocket wheel 77 and an outer sprocket wheel 79 are fixed. A drive chain 81 operatively extends between and around sprockets 73 and 79. A bracket 83 may be fixed to the supporting table from which extends a spring loaded idler sprocket 85 in engagement with chain 81 to take up slack therein. The rubber feed roller 35 has a sub-shaft 35 extending from the same end thereof that shaft 75 extends from roller 19, and a sprocket wheel 87 is fixed thereon, the sprockets 87 and 77 being operatively connected by a drive chain 89 so that when motor 47 is operating roller 19 will be driven thereby and roller 35 will, through chain 89 be driven by roller 19, rollers 19 and 35 being driven at the same rate of speed and in a counter clockwise direction.

Referring particularly to Figs. 1 and 3 of the drawings where I have illustrated my apparatus in operation it will be seen that I may provide any suitable conveyor apparatus designated generally by the numeral 91 for conveying a truss to the clinching apparatus. An assembled truss, designated in its entirety by numeral 93, is placed on the conveyor 91 for feeding into the apparatus, it being understood that the truss consists of a plurality of components two of which, 95 and 97, are illustrated as being joined together by upper and lower metal truss lock plates 99 which extend across adjacent parts of the truss components and are fastened thereto by nails 101. It will be further understood that each truss will have a number of joints joining together adjacent components and will include the truss lock plates and that prior to insertion into the clinching apparatus of this invention each joint will be nailed and the projecting nail ends 103 will be in the position illustrated in Figs. 1 and 3. The assembled and nailed truss will be placed on the conveyor 91 with the projecting nail ends projecting upwardly and will be fed into the apparatus in a manner to be described.

As illustrated it is usual for an assembled truss to have an end part which extends beyond any joint in the truss and this end part 105 enters the apparatus first and is grasped by and between the rubber feed rollers 15 which draw the assembled truss through the apparatus. The lower metal clinch roller 19 is set forwardly relative to the upper metal clinch roller 17 so that it will function as a back up element for the nail heads and will prevent the nails from being forced out of the truss by the action of the upper clinch roller. This action is clearly shown in Fig. 3 of the drawings. As the truss is drawn through

5.

the apparatus the projecting nail ends at each joint will be clinched or bent over as shown in Fig. 3 and strong and structurally sound trusses will be produced, and each nail will be firmly and permanently fastened in position. It will be appreciated that each roller in the apparatus is of sufficient width so that laterally positioned joints will be clinched on one pass through the apparatus.

In the event that trusses were being clinched in which a joint was positioned at an end thereof I propose to temporarily add an extension 105 to the truss so that it may extend between the feed rolls before the joint reaches the clinch rolls in order to automatically feed the truss through the apparatus.

It will be understood that the upper feed roller and the upper clinch roller are vertically adjusted to take care of trusses, the components of which may be of varying thickness and the lower metal clinch roller is mounted for horizontal adjustment in order to set or position it as desired with respect to the upper clinch roller. It will also be recognized that the drive arrangement I have evolved simplifies and makes possible the adjustment of the various rollers involved in the apparatus.

With the motors driving the rollers one truss after another is placed on conveyor 93 and fed thereby into the apparatus which clinches the nails at every joint and ejects the fully completed and assembled truss on a further conveyor 107 adjacent the outlet end of the apparatus.

In Fig. 4 I have illustrated a modified form of apparatus and have used the same reference numerals as hereinbefore used to describe similar parts. This form of my invention provides means whereby the upper rollers 33 and 17 are spring loaded rather than being vertically adjustable to fixed or anchored position as in the form of the invention shown in Fig. 1. In this form of my invention the journal brackets 21 and 37 for the upper rollers have bolts and nuts 23 and 39, respectively, which extend through slots 25 and 41 in walls 11. However, the bolts and nuts on the opposite ends from the journal brackets extend through base elements 108, each of which has an arm 109 fixed to and projecting therefrom, the base elements 108 being slidable with respect to walls 11. A tension spring 111 is fixed to each arm and extends therefrom to a fixed point 113 on supporting members 7. Thus, the upper rollers are biased downwardly toward the lower rollers with sufficient force to cause rollers 33 and 35 to feed the trusses through the apparatus and to cause clinch rollers 17 and 19 to clinch the nails at each joint of the truss. This mounting arrangement provides an inherent automatic adjustable characteristic and permits trusses and joints of different thicknesses to be operated on without requiring manual adjustment. This floating or spring biased mounting of the rollers also automatically takes care of minor variations in thickness which may occur in any truss, and assures full and complete clinching of the nails.

Fig. 5 of the drawings illustrates a further form of my invention, and again I have used the same reference numerals to designate parts which are the same as hereinbefore described. In this form of my invention I have added means forwardly of the clinch rollers 17 and 19 for preliminary operation on the nailed truss which is being fed through the apparatus. I have added a clinch roller 115 which is substantially similar to rollers 13 of the preferred embodiment of the invention. The roller 115 is mounted on front or forward wall 117 of the forward supporting member 7 forwardly of and in the same horizontal plane as clinch roller 17. The roller 115 is mounted for vertical adjustment by means of nuts and bolts 119 which extend through vertical slots 121 in walls 117. The shaft of roller 115 extends outwardly as at 123 and a sprocket wheel 125 is fixed thereon. The shaft 65 of roller 17 has a further sprocket wheel fixed thereon inwardly of sprocket wheel 67 and in horizontal alignment with sprocket wheel 125. A drive chain 127 opera-

6.

tively connects sprocket 125 with the other sprocket or shaft 65 so that roller 115 is driven by roller 17.

A stationary shoe or plate of metal 127 is fixed on bed 1 of the table beneath clinch roller 115 for partial clinching cooperation therewith when a truss is passed therethrough. Clinching rollers 17 and 19 also operate on the joints of the truss and complete the clinching operation. It is preferable that the spacing between roller 115 and stationary clinch plate 127 be greater than that between rollers 17 and 19, as the roller 115 and plate 127 preferably perform only a partial clinching operation.

In Fig. 6 of the drawings I have illustrated another type of truss lock plate which may be fastened to adjacent components of a truss to connect them together. In this figure of the drawings I have used the numerals 95' and 97' to designate adjacent components of a truss which are to be connected together. The connecting means comprises a pair of truss lock plates 99' each of which is formed with struck-out tangs 103' which are adapted to be embedded in the truss components. Fig. 6 shows the truss as it is being fed into the apparatus, with the truss lock plates mounted in position. The rollers 17 and 19 of the apparatus will force the tangs 103' into the wood components so that the plates will be securely fastened thereto. It will be understood that the truss lock plates 99' may be partially fastened to the components of the truss before it is fed into the apparatus for the final fastening operation. It is also to be understood that any nails which may be associated with the plates 99' will also be clinched in the manner set forth above.

It will now be apparent that I have evolved a simple, efficient and economical apparatus for automatically clinching nails in assembled trusses and for fastening truss lock plates to truss components.

I claim:

1. A nail clinching apparatus for clinching the projecting pointed ends of nails extending through and securing connecting elements to and across adjacent components of structural trusses to provide an assembled truss, said apparatus including an inlet end and an outlet end and means for drawing assembled trusses successively into the apparatus through said inlet end and ejecting them from said outlet end following the clinching operation, and rotative means engageable with the projecting pointed ends of said nails for causing the clinching thereof, back up means spaced vertically from said rotative means, and engageable with the heads of the nails as a truss is drawn through the apparatus and between said rotative means and said back up means, said back up means being positioned closer to said inlet end than is said rotative means, and means for causing rotation of said rotative means.

2. A nail clinching apparatus for clinching the projecting pointed ends of nails extending through and securing connecting elements to and across adjacent components of structural trusses to provide an assembled truss, said apparatus having an inlet end and an outlet end, a pair of vertically spaced feed rollers rotatively mounted adjacent said outlet end and provided with frictional surfaces adapted to engage a truss extended therebetween and draw it through the apparatus, a pair of vertically spaced clinch rollers rotatively mounted in said apparatus spaced forwardly of said feed rollers and adjacent said inlet end and provided with metallic surfaces adapted to engage and clinch the nails in a truss as it is drawn through the apparatus, and means for causing rotation of one of said feed rollers, and said one feed roller being operatively connected to one of said clinch rollers for causing rotation thereof, and the other of said clinch rollers being operatively connected to the other of said feed rollers for causing rotation thereof, and means for driving said one of said feed rollers and said other clinch roller.

3. A nail clinching apparatus in accordance with claim

2, wherein said one of said feed rollers is adjustable vertically relative to said other feed roller and said one of said clinch rollers is vertically adjustable and said other clinch roller is horizontally adjustable, and said other clinch roller is adjusted to a position forwardly of and closer to said inlet end than is said vertically adjustable clinch roller.

4. A nail clinching apparatus for clinching the projecting pointed ends of nails extending through and securing connecting elements to and across adjacent components of structural trusses to provide an assembled truss, said apparatus having an inlet end and an outlet end, a pair of vertically spaced feed rollers rotatively mounted adjacent said outlet end and adapted to engage a truss extended therebetween and draw it through the apparatus, a pair of vertically spaced clinch rollers rotatively mounted in said apparatus spaced forwardly of said feed rollers and adapted to engage and clinch the nails in a truss as it is drawn through the apparatus, means causing rotation of said rollers, and a further clinch roller forwardly spaced relative to the upper of said vertically spaced clinch rollers and operatively connected thereto for rotation thereby, and a clinch plate spaced from and below said further clinch roller.

5. A nail clinching apparatus for clinching the projecting pointed ends of nails extending through and securing connecting elements to and across adjacent components of structural trusses to provide an assembled truss, said apparatus including an inlet end and an outlet end and means for drawing assembled trusses successively into the apparatus through said inlet end and ejecting them from said outlet end following the clinching operation, and rotative means engageable with the projecting pointed ends of said nails for causing the clinching thereof, back up means comprising a roller spaced vertically from said rotative means, and engageable with the heads of the nails as a truss is drawn through the apparatus and through and between the rotative means and the back up means, the axis of said roller being positioned closer to said inlet end than is the axis of said rotative

means, and means for causing rotation of said rotative means.

6. Apparatus for securing connecting elements to and across both sides of adjacent components of structural trusses to provide an assembled truss by pressing portions of the elements into said components, said apparatus having an inlet end and an outlet end, a pair of vertically spaced feed rollers rotatively mounted adjacent said outlet end and provided with frictional surfaces to engage a truss extended therebetween and draw it through the apparatus, a pair of vertically spaced pressure rollers rotatively mounted in said apparatus spaced forwardly of said feed rollers and adjacent said inlet end and provided with metallic surfaces adapted to engage and press the portions of the elements into the components of the truss as it is drawn through the apparatus, and one of said feed rollers being adjustable vertically relative to said other feed roller and one of said pressure rollers being vertically adjustable and said other pressure roller being horizontally adjustable, and said vertically adjustable rollers being operatively connected together, one being a drive roller and the other being a driven roller, and power means connected to the drive roller for causing rotation thereof, and said other feed roller and said horizontally adjustable pressure roller being operatively connected together, one being a drive roller and the other being a driven roller, and further power means connected to said last named drive roller for causing rotation thereof.
